UNITED STATES PATENT OFFICE

2,643,591

AUTOMATIC MEANS FOR MAKING SPECIAL
CARDBOARD CONTAINERSLeo D. Overland, Brooklyn, and Jack W. Levine,
Bayside, N. Y.

Application February 15, 1950, Serial No. 144,271

1 Claim. (Cl. 93—49)

1

This invention relates to an apparatus for making cartons from cardboard blanks and particularly cartons for ice cream sandwiches. It was considered desirable to have channels in these cartons, preferably formed by suitably bending the walls of the carton, for the insertion of ice cream wafers.

Difficulties were experienced in the shaping of these channels, since the cardboard is elastic and does not readily retain the shape into which it has been pressed. It was found that any bend, to be permanent, must be exaggerated while heat is applied. Hence, to secure, for instance, a right-angle bend in a cardboard, the bend is folded over to a much larger angle, even by 180 degrees, i. e., it is folded over entirely and pressed in this position. When released it will then retain the bend.

A further problem was the folding-up of the cardboard carton, which it was intended to do fully automatically to secure speed of operation as well as uniformity of result. The bending of the cardboard blank on predetermined lines which may be weakened is accomplished and two sides of the flat blank pasted together so as to form a container.

The method and apparatus according to this invention provide channels in the walls at any desired location, form-up the container from the flat blank, and paste the margins together where necessary.

Other objects and advantages of the present invention will become apparent in conjunction with the following specification and drawings in which:

Fig. 1a is a top view of the first section of a die rolling machine according to one embodiment of this invention and a carton blank;

Fig. 1b is a top view showing the continuation of the die rolling machine shown in Fig. 1a;

Fig. 2 is a cross-sectional view on line 2—2 of Fig. 1a and a carton blank;

Fig. 3 is a cross-sectional view on line 3—3 of Fig. 1a and a carton blank;

Fig. 4 is a cross-sectional view on line 4—4 of Fig. 1a and a carton blank in position;

Fig. 5 is a cross-sectional view on line 5—5 of Fig. 1a and part of a carton blank;

Fig. 6 is a cross-sectional view on line 6—6 of Fig. 1b and a carton blank;

Fig. 7 is a cross-sectional view on line 7—7 of Fig. 1b and a carton blank;

Fig. 8 is a cross-sectional view on line 8—8 of Fig. 1b and a carton blank;

Fig. 9 is a cross-sectional view on line 9—9 of Fig. 1b and a carton blank;

2

Fig. 10 is a front view of the glue applying rollers at line 10—10 in Fig. 1b and a cross-sectional view of a carton;

Fig. 11 is a front view, partly in section, at line 11—11 of Fig. 1b;

Fig. 12 is a top view of part of a die rolling machine according to another embodiment of this invention and a carton blank;

Fig. 13 is a cross-sectional view on line 13—13 of Fig. 12 and part of a carton blank;

Fig. 14 is a cross-sectional view on line 14—14 of Fig. 12 and part of a carton blank;

Fig. 15 is a front view at line 15—15 of Fig. 12 and part of a carton blank in section;

Fig. 16a is a top view of part of an apparatus according to still another embodiment of this invention;

Fig. 16b is a top view of the continuation of the apparatus shown in Fig. 16a;

Fig. 17 is a cross-sectional view on line 17—17 of Fig. 16a;

Fig. 18 is a side view, partly in section, on line 18—18 of Fig. 16a and a carton blank;

Fig. 19 is a top view, partly broken away, of an apparatus according to a further embodiment of this invention;

Fig. 20 is a side view, partly in section, on line 20—20 of Fig. 19 and a carton blank;

Fig. 21 is a cross-section on line 21—21 of Fig. 20;

Fig. 22 is a cross-sectional view illustrating a modification of the embodiment of the apparatus shown in Fig. 19; and

Fig. 23 is a perspective view of a carton with channels produced according to this invention.

Referring to Fig. 1a, a series of preformed carton blanks connected by perforated or otherwise weakened lines 1 is fed into the die rolling machine by means of feed rollers, such as 2. Each carton has four side walls, 3, 4, 5 and 6, a flap 7 to be pasted onto the outer margin of side wall 6 when the carton is formed-up, and a lid 8 provided with a flap 9 which is tucked inside the carton when the lid is closed.

Referring also to Fig. 2, the side walls 5 of the carton blanks are advanced by guide rollers 10, mounted on rotatable shafts 11 and 18. It will be seen that a series of pairs of shafts 11 and 18 are rotatably supported by brackets 16 mounted on a base 17. The motor-driven chain 20 rotates the wheels 19 rigidly connected to shafts 11. Driving gear wheels 21 on driven shafts 11 cooperate with driven gear wheels 22 to rotate the lower shafts 18. Further each of shafts 11 and 18 is provided with a steam pipe 23 for heating of the dies supported by the shafts.

Die rollers 12 and 13 press side wall 3 of the carton into an arcuate central section 14 bounded by shoulders having flat sections 15 which form an acute angle with the central section 14.

Several identical stages may be supplied, if necessary, though only one stage is illustrated for this as well as the following operations.

Fig. 3 shows the next die rolling profile. The central section of the profiles of dies 24 and 25 are identical with those of dies 12 and 13. However, further two acute angles are die rolled into the carton wall 3, separating the flat sections 15 from newly formed slanting sections 26.

The subsequent stages are provided with narrow advance rollers 28 curved to fit the arcuate section 14 of wall 3.

Die roller 27 is of identical shape with die roller 12 and cooperates with a further die roller, not shown, identical with die roller 13, to impress arcuate and flat sections, corresponding to sections 14 and 15, in wall 5 of the cardboard blank. Similarly, die roller 29 of identical shape with die roller 24, cooperates with a die roller, not shown, to give the wall 5 a shape identical with that of wall 3 obtained between die rollers 24 and 25.

Referring now to Figs. 1, 4 and 5, advance rollers 29 and 30 push the carton blank between the guide plate 31 and the support 32 mounted on base 17 by means of the central leg 34. Bending guides 33 extend horizontally where they engage the walls 3 and 5 of the cardboard carton and gradually swing downwards to extend vertically where the walls leave that section. It is the purpose of these bending guides to form-up the carton by bending the blank at the lines, which may be weakened, between walls 3 and 4 and walls 4 and 5, respectively.

Fig. 1b is a continuation of Fig. 1a and illustrates the subsequent forming operations in conjunction with Figs. 6 to 11.

Alternately arranged forming rollers 36 cooperate with flanged rollers 35, see Figs. 1b and 6, to impress the previously formed channels in walls 3 and 5. The support 31 is also profiled to accentuate the channels in these walls.

In the next step, illustrated in Figs. 1b and 7, the bending guide 38 folds the line extending between the wall 3 and the flap 7. The bending guide 38 is shaped similar to the bending guides 33, however, its effective sections are located below the support 32 and it starts from a vertical position gradually changing to a horizontal position; Fig. 7 illustrates an in-between state, as will be observed from the location of the dotted line 7-7 in Fig. 1b.

Fig. 8 in conjunction with Fig. 1b illustrates the application of glue from the glue container 41 by means of the rotating wheel 39 onto the flap 7, the flap being held against upward movement away from wheel 39 by wheel 40.

Wall 6 is now moved upward and towards the glued side of flap 7 by guide 41A, shown in Figs. 9 and 1b. This guide is constructed according to the same principle as guides 33 and 38.

Two rollers, 42 and 43, Figs. 10 and 1b, now press the wall 6 against the glued side of the flap 7 to secure good adhesion of these parts.

The motor 44 drives the chain 20 over the transmission 45, 46, 47 and 48, as shown in Fig. 1b.

Figs. 11 and 1b illustrate the severing of two adjacent cartons along the preformed line between the flap 9 of the first carton and the wall 4 of the subsequent carton. A guide 49 holds

the wall 4 against the support 32, while a cutter 50 is moved downward by any suitable means, not shown, as the springs 51 are compressed, separating the two cartons along the line 1.

In the embodiment of this invention illustrated in Fig. 12, the first two stations on the die rolling machine correspond to the first two channel-forming stations shown in Fig. 1a. However, a further pressing operation, Figs. 12 and 13, between a support 53, provided with shaping edges 54, and a shaping plate 55 serves to bend and tightly fold the channel walls formed in wall 3.

Figs. 14 and 12 illustrate the holding plate 56 preserving the folds in wall 3 in conjunction with support 53 until the folded wall is further pressed by rollers 57, Figs. 15 and 12, bending all previously impressed folds to nearly a 180 degree position so that these folds will be certain to retain their shape.

The further steps in this embodiment are identical with those of the embodiment previously described in connection with Figs. 1a to 11, except that a further pressing operation will be inserted to securely bend the folds impressed in wall 5.

Figs. 16a to 18 illustrate further features which may be incorporated in a die rolling machine according to this invention.

Figs. 16a and 17 show a feeding mechanism for a stack of separate carton blanks 58. The reciprocating feeder 59, operated by any suitable mechanism, not shown, pushes each carton 58 until its movement is arrested by stop 62. The carton is then in a position to be gripped by the guiding bands 60 and 61 actuated by rollers 63, respectively.

In this embodiment, the first operation is the bending of the predetermined separation lines between walls 3 and 5 and wall 4. Bending guides 64, extending first horizontally above the location of the walls 3 and 5 to be bent and gradually swinging to a vertical position as the carton is moved along the support 65, perform the bending operation.

The channel-forming operation, Figs. 16a and 18, is done by die rollers 66, 67, 68, 69, 70, 71, 72 and 73 which are similar to die rollers 12, 13, 24, 25, 27 and 29 of Figs. 1a, 2 and 3. However, in the present embodiment, the die rollers are mounted and rotatable on vertical axles, such as 74 and 75. Axle 74 is driven by toothed wheel 76 and chain 77, while the axle supporting die roller 71 carries a toothed wheel 80 which is driven by a chain 79 actuated by the toothed wheel 78 on axle 74. The supporting axles for the die rollers 66 and 68 are similarly driven by a toothed wheel and chain arrangement 81, 82, 83, 84, 85 and 86.

Fig. 16a further shows the bending guide 87 for the flap 7 and the following glue pot 88 and the wheel 89 cooperating with another wheel, not visible in Fig. 16a, to apply glue to flap 7. These steps have been described in detail in conjunction with Figs. 1b, 7 and 8.

Fig. 16b illustrates the bending guide 90 for wall 6 and the roller 91 cooperating in the pressing of flap 7 against wall 6 in the final step of the pasting of the carton. These steps have been described in more detail in connection with Figs. 1b, 9 and 10.

The motor 92 drives the chain 20 via the transmission 93, the wheel 94 and the toothed wheel 95.

A further embodiment of this invention is illustrated in Figs. 19, 20 and 21.

After insertion of the carton blank into the die press, guides 96 bend walls 3 and 5 into a vertical position, as previously described. The channel-forming operation is simultaneously performed on both walls 3 and 5 in the following step illustrated in Figs. 19 and 20.

In this embodiment, a step-wise operation takes place. The carton blank is moved to each stage in the process, remains there until the action is completed, and is then advanced to the next stage. Hence motor 121, driving chain 20 over transmission 122, wheel 123 and sprocket wheel 124, is intermittently operated by a suitably timed switch, not shown. The power press actuating the forming dies is synchronously controlled, for instance by a cam, not shown.

The carton is passed automatically onto a horn 97 and held in place by roller 98. The horn profiles 101 cooperate with dies 99, secured to the die holders 100, in the formation of the channels. The die holders 100 are slidably mounted in the channels of supports 102, as illustrated in Fig. 21, and forced outwards by springs 103. The press-operated plunger 104 has two tapered extensions 105 sliding on the sloping walls 106 of the die holders 100, urging them inwardly against springs 103. This movement will cause the dies 99 to be urged against the forming profiles 101 of the horn 97, thereby forming channels in walls 3 and 5 of the carton.

The further steps of bending flap 7 by bending guide 107, providing glue thereon by glue pot 108 and wheel 109, bending wall 6 by bending guide 110 and completing the pasting of wall 6 onto flap 3 by wheel 111 are as previously explained.

Fig. 22 illustrates another embodiment, similar to that shown in Figs. 19 to 21, where the stamping of the channels is done before the bending downward of walls 3 and 5. Hence the carton blank is still in a horizontal position and the two walls 3 and 5 are located in the same horizontal plane.

The support 112 carries two dies 113 and 114 for the walls 3 and 5, respectively. However, these dies are displaced in the direction of advancement of the carton blanks, since simultaneous formation of channels in both walls, 3 and 5, would tend to foreshorten and tear the material between these two walls. Hence, though simultaneously operative, the two dies 113 and 114 simultaneously shape the walls of different, preferably adjacent, carton blanks. The press-operated plunger 104 carries the die holder 118 which in turn carries dies 119 and 120 having spring-loaded inserts 121 and 122, respectively.

It will be seen that the die rolling or forming press according to this invention may assume various different modifications.

Fig. 23 illustrates the finished carton, flap 7 pasted onto the margin of wall 6 and having two pairs of channels 119 and 120. This carton, formed by the method and apparatus just

described, is made from a cardboard blank by roll forming. Channels are impressed and the carton is formed up along lines separating the walls of the carton; these lines may be weakened in the carton blank. Also, there may be provisions for gluing a flap on one of the outermost side walls of the carton blank to the free margin of the other outermost side wall so that the side walls of the carton assume a closed shape. All of these steps are fully automatic, assuring speed of operation and uniformity of result.

It is understood that various modifications may be made in the form and arrangement of the elements constituting the embodiments illustrated and described without departing from the spirit of the invention.

Having thus described our invention, what we claim and desire to secure by Letters Patent is as follows:

- 20 A roll press for forming a channel in a cardboard, comprising a first pair of rotatably mounted, cooperating forming rollers and a second pair of rotatably mounted, cooperating forming rollers, the profile of one roller of the first pair of forming rollers having a central channel between two rounded shoulders, the bottom wall of said channel having an arcuate shape, the second roller of said first pair having a projection on its forming profile, said projection fitting into the channel of said first roller and having a fittingly curved bottom wall, the profile of one roller of said second cooperating pair of rollers having a central channel between two outwardly bevelled shoulders, said channel having an arcuate bottom wall, the second roller of said second pair having two channels located opposite and fitting onto the outwardly bevelled shoulders of said first roller and an arcuate central section fitting onto said arcuate bottom wall of said channel in said first roller, means for heating said forming rollers, and means for passing the cardboard between said first pair of rollers and then between said second pair of rollers in aligned positions, whereby first a channel with rounded shoulders is impressed upon the carton and subsequently a channel with bevelled shoulders is superimposed on the first formed channel.
